S. JOHNSEN.

AUTOMATIC CLOCK CONTROLLED SWITCH OPERATING DEVICE,
APPLICATION FILED DEC. 19, 1919.

1,393,447.

Patented Oct. 11, 1921.

UNITED STATES PATENT OFFICE.

SVEND JOHNSEN, OF WINNIPEG, MANITOBA, CANADA.

AUTOMATIC CLOCK-CONTROLLED SWITCH-OPERATING DEVICE.

1,393,447.

Specification of Letters Patent. Patented Oct. 11, 1921.

Application filed December 19, 1919. Serial No. 346,094.

To all whom it may concern:

Be it known that I, SVEND JOHNSEN, a subject of the King of Great Britain, of the city of Winnipeg, in the Province of Manitoba, Canada, have invented certain new and useful Improvements in Automatic Clock-Controlled Switch-Operating Devices, of which the following is the specification.

10 The invention relates to improvements in automatic clock controlled switch operating devices and the principal object of the invention is to devise a simple means whereby an electrical switch may be automatically operated after a predetermined interval of time.

20 A further object is to arrange the appliance as a permanent attachment to an alarm clock and such that the various spindles of the clock can be manipulated in the ordinary way for setting or winding purposes.

25 A still further object is to construct the parts in an inexpensive, easily assembled and durable manner.

With the above objects in view the invention consists essentially in the arrangement and construction of parts hereinafter more particularly described and later pointed out in the appended claim, reference being had 30 to the accompanying drawing in which:—

Figure 1 is a front view of an alarm clock fitted with my attachment.

Fig. 2 is a side view thereof.

35 Fig. 3 is a rear view of the clock with the attached casing removed, to show the working parts.

Fig. 4 is a perspective view of a modified arrangement of switch.

In the drawing like characters of reference indicate corresponding parts in the several figures.

1 represents an alarm clock of ordinary type which is provided as is customary at the rear with a main winding stem 2, the 45 main hand setting stem 4, the alarm hand setting stem 3 and the alarm winding stem 5. Under ordinary conditions the ends of these stems which protrude beyond the back of the clock are provided with finger pieces 50 for operating purposes.

These I dispense with and to them I attach controlling spindles later described which are actually extensions of the stems.

To the back of the clock I secure permanently by bolts 6 and 7 a vertically disposed insulating block 8, the stem 5 actually pro-

truding through this block. On the block I mount an L-shaped bracket 9 which is fastened to the block by the bolts. The lower part of the bracket extends rearwardly 60 at right angles from the clock and is provided with two outstanding wings 10 and 11 and two upstanding lugs 12 and 13. To the wings I secure permanently as by screws 14 a horizontally disposed base plate 15 of 65 insulating material. To the plate I fasten two contact bars 16 and 17 fitted with substantially V-shaped contact ends 18 and 19 which overhang the plate 15.

20 and 21 are electrical lead wires connected to the bars and leading to a screw plug 22. In the present instance in the wire 20 I insert a lamp socket 23 supplied with an electric lamp 24.

25 represents a knife switch adapted to 75 make electrical contact with the ends 18 and 19 of the bars. This switch is carried by a substantially L-shaped rocker arm 26 pivotally mounted on a cross pin 27 carried by the lugs 12 and 13. 28 is a flat spring 80 fastened by the bolt 6 and engaging the upwardly extending part of the rocker arm and designed to normally hold the knife switch down or out of contact with the bar contacts.

To the upper end of the rocker arm I connect a setting bar 29 which extends to the side and is utilized when pressed toward the clock to put the knife switch in contact with the ends 18 and 19 of the bars 16 and 17 and thereby close the circuit through the wires 85 20 and 21.

The parts so attached to the back of the clock are all inclosed within a cylindrical casing 30 fastened to the clock by suitable 95 side clips 31. 32, 33, 34 and 35 are independent extension spindles having their forward ends connected to the stems 2, 5, 4 and 3 respectively and their rear ends projecting out through the back of the casing 100 30 and fitted with suitable finger grips 36. These spindles are simply extensions to the back of the casing to allow of the manipulation of the stems after the casing has been fastened to the clock. The casing is fitted 105 with a side slot 37 and when the parts are assembled the setting bar 29 extends outwardly through the slot.

To the spindle 33 I secure a pair of outwardly extending diametrically opposing 110 lugs or ears 38 and 39, one of which in the outwardly pressed position of the free end

of the rocking bar is adapted to pass behind the rocking bar and so hold it set in its forward position and with the knife switch open.

5 While I have described a lamp in the circuit, it will be readily understood that any electrical appliance could be placed in the circuit at this point which appliance would be controlled directly by the operation of 10 the switch.

Assuming a lamp used and that one wishes that the lamp be turned off at a predetermined time, it is only necessary to turn the alarm spindle 35 to set the alarm hand 15 at the selected time, then wind the alarm spindle and just before the winding is finished to press the lever 29 ahead so that when one has completed the winding action the free end of the bar 26 will be held against 20 moving backwardly by contact with one of the lugs 38 or 39. Then, by screwing the plug 22 into the ordinary lamp socket which communicates with a source of electro-motive force the appliance can be left and will 25 automatically work to extinguish the lamp just as soon as the said hour has arrived. This action occurs in the following way:—

At the time the alarm goes off the stem 5 turns, with the result that the lug 38 or 39 30 swings away from the rocker bar 26 and the freed rocker bar is immediately swung over by the spring to break contact at the knife switch.

In Fig. 4 I have shown a modified form 35 of contact and knife switch which if supplied instead of that shown in Fig. 3 will act to turn on the light at a set time instead of turn it off. This is accomplished by simply reversing the position of the contacts 40 18 and 19 in respect to the knife switch so

that the knife switch is normally in contact when the rocker arm is in the position as shown in Fig. 3 and is out of contact when the rocker arm is set engaged with one or other of the lugs 38 and 39.

45

As this is such an obvious change, being simply the reverse from an electrical standpoint of the action shown in Fig. 3, I have not entered into a minute description of it and do not desire to be limited to either one 50 or other of the knife switch arrangements when constructing as this would simply be a matter of choice, depending on whether one desired the circuit open or closed at the time the alarm goes off.

55

What I claim as my invention is:—

A time controlled switching device comprising a base plate, stationary contacts mounted thereon, an L shaped bracket mounted on said base plate, an L-shaped contact having the lower horizontal arm thereof pivotally supported upon the corresponding arm of said bracket and arranged to cooperate with said stationary contacts, a spring interposed between the vertical arms of the bracket and contact normally tending to force the latter outwardly from the bracket, a handle operative to move the bracket to a set position against the resistance of said spring, and releasable means engageable with said bracket to hold the same in a set position for a definite period of time adapted to automatically release the contact at a predetermined time.

Signed at Winnipeg, this 25 day of November, 1919.

SVEND JOHNSEN.

In the presence of—

G. S. ROXHUGH,
H. B. WAKEFIELD.
